(57) **CLAIM**

The ornamental design for a paper plate and cup holder, as shown and described.

DESCRIPTION

FIG. 1 is a bottom perspective view of a paper plate and cup holder showing our new design;
 FIG. 2 is a bottom plan view thereof;
 FIG. 3 is a top plan view thereof;
 FIG. 4 is a left elevational view thereof;
 FIG. 5 is a right elevational view thereof;
 FIG. 6 is a front elevation view thereof; and,
 FIG. 7 is a back elevation view thereof.
 Objects shown in broken lines are shown for environmental purposes only and form no part of the claimed design.
